UNITED STATES PATENT OFFICE.

HARRY R. JACKSON AND HENRY A. MAY, OF CHICAGO, ILLINOIS.

GOVERNING VALVE FOR INTERNAL-COMBUSTION MOTORS.

1,408,887.

Specification of Letters Patent.

Patented Mar. 7, 1922.

Application filed December 2, 1920. Serial No. 427,907.

To all whom it may concern:

Be it known that we, HARRY R. JACKSON and HENRY A. MAY, both citizens of the United States, residing at Chicago, in the county of Cook and State of Illinois, have invented a certain new and useful Improvement in Governing Valves for Internal-Combustion Motors, of which the following is a specification.

10 Our invention relates to valves for automatically governing the flow of gas into internal combustion engines. One of the objects is to provide means for automatically limiting the speed of the vehicle regardless 15 of the position of the throttle. Briefly, we accomplish this by introducing into the intake duct which leads to the intake manifold a valve mechanism so constructed that the valves or gates will automatically decrease 20 the available size of the opening in proportion to the speed of the engine. Another object is to provide means for obtaining a venturi effect and to deflect the gas from the side to the central portion of the 25 duct to prevent condensation upon the walls of the duct, especially at slow engine speeds when the walls of the duct are cold. In a companion application filed by us on the second day of December, 1920, Serial Number 30 427,906, we have shown mechanism for a somewhat similar purpose so far as deflection and venturi effect is concerned, but in that case the gates or valves do not function to limit the engine speed. Our present purpose 35 is to promote economy in gas consumption and also to limit the rate at which the engine can draw fuel from the carburetor.

We obtain our objects by the mechanism illustrated in the accompanying drawings 40 in which—

Figure 1 is a front elevation of the device shown assembled with the intake manifold and throttle valve of an internal combustion engine.

45 Figure 2 is a plan section on the line 2—2, Figure 1.

Figure 3 is a vertical section on the line 3—3, Figure 2 and

50 Figure 4 is a vertical section on the line 4—4, Figure 3.

Figure 5 is similar to Figure 3 but shows the governing gates in open, non-acting position.

Like numerals denote like parts through 55 out the several views.

The intake manifold 1 is fed through an intake duct which in the present case is formed in two sections 2, 3, separated by a connecting section 4. The sections 2 and 3 are flanged so that they may be bolted to section 4. Section 4 has a central opening 6 which becomes a portion of the intake duct. Below the connecting section 4 is a throttle valve 8 mounted on a rock shaft 10 and controlled by a lever arm 12 in the ordinary manner. Throttle 8 is manually controlled and, subject to our special device, forms the means for controlling the speed of the engine and vehicle.

Mounted within the connecting section 4 are two rock shafts 14. They are arranged horizontally and by preference are partially embedded in the side walls of the section, as best shown in Figure 4. These rock shafts form supports for the main sections 15 of the controlling gates. The free edges of these gates are hinged to front sections 16, the latter having pins 17 at the free ends which project into slots 18 near the walls of the section for guiding purposes.

The rock shafts 14 project at one end 80 through the walls of the section 4 and are there fastened to arms 20, 21, as best shown in Figure 1. The arm 20 is slotted to receive a pin 22 which is fastened to arm 21 85 and slides in the slot of arm 20 to cause the two gates to always swing equal amounts and in unison. The gates are constantly urged toward open position by a spring 22 which is fastened at one end to the pin 20 90 and at the other end to an adjusting screw 24. The end of the spring nearest to the screw is coiled and the tension of this coil can be increased or decreased by making the proper adjustments by the aid of screw 24. 95

In operation, when the throttle is closed, there will be no appreciable flow of gas and the spring 22 will hold the gates wide open. If, now, the throttle is gradually opened it will permit the gas to flow upward in the 100 intake duct, and as the gas flow increases, it presses harder and harder upon the gates and gradually moves them toward closed position. At the same time there is a vacuum created on the back face of the gates which 105 assists in urging the gates toward closed position. The parts are so designed that at maximum permissible engine speed the gates will occupy the closed position shown in Figure 3. The passage will not be entirely 110

shut off but will be restricted and the amount of gas flowing through will be just sufficient to drive the vehicle at the maximum permissible speed under ordinary running conditions. If an upgrade is encountered or the road is heavy, the engine speed will of course fall off even though the throttle may be wide open. This will decrease the velocity of the gas stream and 5 the gates will automatically move a corresponding amount toward open position. Thus the gates open up to increase the fuel supply to the engine when the latter requires it, but as soon as the engine has 10 gained its speed, will again restrict the fuel flow. This action not only serves to limit 15 the speed of the engine, but also promotes economy, for at high speeds a smaller relative amount of fuel will be permitted to 20 pass.

In addition to the effect of limiting the speed and promoting economy, our valve mechanism produces a venturi effect which still further promotes economy. Besides 25 restricting the opening, the front section 16 of the gates deflects the gas from the side walls toward the center of the duct and thus prevents condensation.

Having thus described our invention what 30 we claim as new and desire to secure by Letters Patent, is:—

1. The combination with the intake duct of an internal combustion engine of a pair of gates located on opposite sides of the 35 duct, each gate consisting of a main section which is hinged directly to the wall of the intake and another section which is hinged to the free edge of the main section.

2. The combination with the intake duct of an internal combustion engine of a pair 40 of gates located on opposite sides of the duct, each gate consisting of a main section hinged to the side of the duct and facing upstream, and a second section pivoted at one end to the free end of the main section, the 45 free end of the second section being constrained to move in a path parallel and adjacent to the side of the duct.

3. The combination with the intake duct of an internal combustion engine of a pair 50 of gates located on opposite sides of the duct, each gate consisting of a main section hinged to the side of the duct and a second section pivoted at one end to the free end of the main section, the duct having guides 55 parallel and adjacent to its sides on the upstream side of the main section of the gate for guiding the free end of the second section of the gate, and means for urging the gates to swing upstream.

4. The combination with the intake duct of an internal combustion engine of a pair of gates located on opposite sides of the duct, each gate consisting of a main section hinged to the side of the duct and facing 6 upstream, a second section pivoted at one end to the free end of the main section, the free end of the second section being constrained to move in a path parallel and adjacent to the side of the duct, and means for 7 equalizing the movement of the two gates.

In witness whereof, we have hereunto subscribed our names.

HARRY R. JACKSON.
HENRY A. MAY.
